UNITED STATES PATENT OFFICE.

HENRY EMMANUEL HALLBORG, OF NORFOLK, VIRGINIA, AND HAROLD REDMORE MILLER, OF WASHINGTON, DISTRICT OF COLUMBIA.

WIRELESS TELEGRAPH APPARATUS.

Application filed June 6, 1921. Serial No. 475,278.

To all whom it may concern:

Be it known that we, HENRY EMMANUEL HALLBORG and HAROLD REDMORE MILLER, citizens of the United States, and residents 5 of Norfolk, in the county of Norfolk and State of Virginia, and Washington, in the District of Columbia, respectively, have invented certain new and useful Improvements in Wireless Telegraph Apparatus, of 10 which the following is a specification.

Our invention relates to improvements in wireless telegraph apparatus, and it consists in the constructions, combinations and mode of operation herein described and 15 claimed.

The foremost object of the invention is to provide means in a wireless telegraph apparatus for rendering the telephones inoperative while the key is depressed in the 20 transmitting position.

A further object of the invention is to provide a wireless telegraph apparatus, including a receiving system which embodies a low reactance condenser for short circuiting the telephones when the operating key 25 is depressed to the transmitting position.

A further, but secondary, object of the invention is to provide an improved break key, the special construction of which plays 30 an important part in the operation of the improved wireless apparatus.

Other objects and advantages will appear in the following specification, reference being had to the accompanying drawings in 35 which:—

Figure 1 is a diagram of a wireless telegraph apparatus, illustrating both the application of the shunt-condenser and the improved manual break key,

Figure 2 is a diagram illustrating the application of the aforesaid elements of the invention to a spark system having a vacuum tube and amplifier system of reception,

Figure 3 is a side elevation of the manual break key used in connection with the improved wireless apparatus,

Figure 4 is a side elevation illustrating the main contact in detail, parts being shown in section for this purpose,

Figure 5 is a section on the line 5—5 of Figure 3, clearly illustrating how the lifting screws for the auxiliary contact levers are mounted on the main key lever,

Figure 6 is a cross section on the line 6—6

of Figure 3, illustrating the main trunnion 55 of the key lever,

Figure 7 is a cross section on the line 7—7 of Figure 3, illustrating the auxiliary trunnions of the auxiliary contact levers,

Figure 8 is a detail section taken substantially on the line 8—8 of Figure 10, illustrating the auxiliary contact lever in the telephone shunting condenser circuit,

Figure 9 is a detail cross section on the line 9—9 of Figure 8, illustrating the contacts of the telephone shunting condenser circuit,

Figure 10 is a plan view of the break key, and

Figure 11 is a detail sectional view illustrating a modification of the main trunnion in Figure 6, wherein the key lever is mounted on adjustable screws which are fixed by jam nuts.

As indicated in the general objects of the invention above, the foremost purpose of the invention is to provide means to be used in connection with any of the well known wireless telegraph systems, for deadening the sounds in the telephone, especially during the transmitting operation, so as to entirely obviate the prevailing annoyance of the operator. This feature of the invention is easily and well explained in connection with Figures 1 and 2 of the drawings. The 75 apparatus in Figure 1 embodies a vacuum tube transmitter, a vacuum tube detector and amplifier, while the transmitter in the apparatus in Figure 2 is of the spark type 80 but also embodies a vacuum tube detector 85 and amplifier.

Attention is first directed to Figure 1. The condenser 63, on the operation of which much importance is attached as indicated above, is connected in shunt around the telephones 64. A wire 65 runs from one side of the condenser to the tip 60 of the manual break key illustrated in Figure 3 et seq., the companion contact tip 59 being connected by the wire 66 to one side of the telephones 64. A wire 65^a is connected between the remaining sides of both the condenser and telephones and this wire joins the battery B which furnishes current to the plate circuit again referred to below.

An AC generator 4 furnishes current for the transmission of signals. 68 designates the receiver of the apparatus in a general

way. The apparatus includes the vacuum tube detector 69 and the first and second stage audion amplifiers 70 and 71. The wires 5 and 6 of the generator 4 are respectively connected to the tips 10 and 23 of the main contact A of the manual break key. Wires 72 and 73, respectively terminating at the tips 61 and 62 of the auxiliary contact b, shunt the primary of the receiving set 68 when the auxiliary contact b is closed.

The transmitting vacuum tubes are designated 76 and 77. The plate 78 of each is connected by a wire 82 to the secondary winding 83 of the transformer 84, which supplies current for the plate circuits. When the main contact A is opened, the current for the plate circuits is cut off, and the vacuum tubes 76 and 77 therefore have no detrimental effect on the reception of signals. The schedule of operation of the apparatus in Figure 1 is as follows:

Contacts	Sending position	Receiving position
25 A-----	Closes generator 4-plate transformer circuit 82 supplying voltage to plates of transmitting tubes 76, 77.	Opens generator-plate transformer circuit cutting off plate voltage.
a-----	Connects condenser 63 of low reactance in shunt to telephones 64.	Disconnects condenser making phones operative for reception with amplification.
30 b-----	Short circuits primary of receiver 68, completing transmitting circuit.	Cuts in primary of receiver completing receiving circuit.

The spark system in Figure 2, is generally like the apparatus in Figure 1, of course with the exception that the vacuum tubes 76 and 77 are omitted. It includes the spark transmitter 67. The receiver 68, audion detector 69 and first and second stage amplifiers 70 and 71 are substantially alike in both cases, as are also the various wiring arrangements in connection with the manual break key. Similar reference characters indicate like parts in both diagrams. The operation of the spark system may be readily followed in the following schedule:

Contacts	Sending position	Receiving position
50 A-----	Closes generator-transformer circuit 4.	Opens generator-transformer circuit 4.
a-----	Connects condenser of low reactance 63 in shunt to telephones 64.	Disconnects condenser 63, making phones 64 operative for reception with amplification.
b-----	Short circuits primary of receiving set 68, completing transmitting circuit.	Cuts in primary receiver, completing receiving circuit.

Particular attention is directed to the purposes and method of operation of the shunt condenser 63. The receiving circuit employing a vacuum tube for the purposes of either detecting or amplifying the received signal, requires a current of small value to be maintained through the telephone continuously during the entire time that the device is in operation. The response in the

telephones is caused by signal waves superimposed on this steady current. The steady current is furnished by the battery B of the plate circuit.

Experience has demonstrated that it is 70 impractical to deaden the telephones during the time that the key is closed in the transmitting position, by opening any part of the audion or receiving circuit which would produce the desired effect, because the disturbance resulting especially with an amplified signal to the extent of two or more stages as shown for example in Figures 1 and 2, produces noises in the telephone which seriously annoy the operator. 75

By means of the condenser 63, the desired effect is obtained. Without disturbing in any way the rest of the receiving circuit, this condenser by-passes from the telephones all other than the steady current from the battery B; previously mentioned, when it (the condenser) is connected around the telephones. The closure of the auxiliary contact a of the key, completes the shunt circuit. The effect of the completion of this circuit is to render the telephones insensitive from induction during the time that the key is depressed and the by-pass circuit is closed, and to place the receiving circuit in instant operation immediately that the key is released and the by-pass circuit again opened. All this is done without causing any disturbances which would annoy the operator. 80

Particular emphasis is laid on this feature 100 which allows the break-key principle to be applied to modern receiving circuits employing amplifiers to enable the reception of weak signals. The condenser 63 must have a very low reactance as compared with the telephones, so that the currents may readily pass around the telephones. A value of .1 105 mf. has been found satisfactory for the type of telephones in ordinary use, for radio reception. 110

The timing of the engagement of the tips 59 and 60 of the auxiliary contact a which complete the shunt condenser circuit and the receiver protective circuit relative to the main contact, is important and must be adjusted slightly in advance of the latter; in other words, the shunt condenser contact a closes first and opens last. Actual details of construction of the manual break key itself are not of great importance, so long as the conditions described above are complied with. However, the key illustrated in the accompanying drawings is considered well adapted to the purpose of the invention and although by no means claimed as the only construction or mechanical arrangement by which the principles of the invention can be satisfactorily carried out, is nevertheless described in detail so that the reader may obtain a good idea as to how it works. 115 120 125 130

The base 1 is composed of suitable insulating material and may be secured, for example, to a table by means of the brass studs 2 and 3. These studs are chiefly employed 5 for connecting the 500 cycle generator 4 in Figure 2 to the main key lever, through the wire connections 5 and 6 which are secured at the washers and check nuts 7 and 8.

For the purposes of subsequent description, 10 the key comprises three principal contacts: The main contact A, the telephone shunting condenser auxiliary contact *a*, and the receiver primary auxiliary contact *b*. The main contact A includes the contact base 9 of brass, into which the upper end of the front stud 2 is sweated so as to make a permanent connection. The end of the stud is drilled and tapped so that the silver contact 10 may be screwed into place.

20 At the rear of the base 1 the stud 3 passes up into the trunnion 11 of the main key lever, where it is secured by being sweated into place. The trunnion is held in position by the screws 12 which pass up from beneath, the heads occupying counter bores as shown in Figure 6. The trunnion 11 is composed of a metallic composition.

In the center of the base are the auxiliary contact trunnions 13 and 14 of the contacts 30 *a* and *b* respectively, both being made of a metallic composition and secured to the base 1 by screws 15 as in Figure 7. Farther front are the auxiliary contact bases 16 and 17, both made of a metallic composition, 35 and each secured by a screw 18 as shown in one instance in Figure 3. The description of

The main key lever 19 is now in order. This key lever, as well as the other moving parts, is intended to be made of metal of 40 low specific gravity, as for example, aluminum, or compositions thereof, in order to reduce the mechanical inertia of such moving parts. This key has a button 20 of insulating material and a guard disk 21 also 45 of insulating material. There is a downward protuberance 22 near the front, drilled and tapped for the reception of the silver contact 23 which coacts with the other silver contact 10, previously described. These 50 two are the only silver contacts; the others are made of copper. Obviously, other material may be employed as may be deemed expedient for any of the contacts.

Bosses 24 on the main key lever carry insulating plugs 25 in which brass bushings 26, 27 are mounted and suitably secured against turning. These bushings carry the lifting screws 28, 29, which have knurled heads 30 at the top and shanks 31 with heads 32 at the bottom. The lifting screws are 60 adjustable in the bushings and the adjustments are fixed by check nuts 33.

A central enlargement 34 carries the spring screw 35 which has a knurled head 36 65 at the top for turning. The main spring 37

is adjusted in tension by the screw 35. The adjustments are fixed by the check nut 38. The base of the spring seats in a hole 39 in the insulating base 1.

The standard 40 of the main trunnion 11 carry a shaft 41 on which the main lever rocks. The ends of the shaft are fixed at 42. The copper braid connector 43 secures a good electrical connection between the movable key lever and the metallic main trunnion 11, from which current is conducted by way of the rear stud 3 as already explained.

Screws 44 secure the connector to the key lever and trunnion respectively. The sub-screw 45 fixes the degree of vibration of the 75 main key lever. The lower end of the screw strikes the pad 46 on the trunnion. Like the other screws of the key lever, it has a knurled head 47 and a check nut 48 for fixing the adjustment.

The auxiliary contacts *a* and *b* comprise levers 49 and 50 fixed by means of screws 51 on spindles 52 which are journaled in the standards 53 of the auxiliary trunnions 13 and 14 mentioned before. Copper braid 80 connectors 54 are fastened to the auxiliary levers by the screws 51 which secure the latter to the spindles 52, and to the auxiliary trunnions 13 and 14 by means of screws 55, for the purpose of making good electrical 85 connections between the movable levers and trunnions.

The ends of the auxiliary levers are bifurcated at 56, as shown for example in Figure 8, to straddle the shanks 31 of the lifting 100 screws 28, 29. When the main lever 19 is raised by the spring 37 upon releasing the button 20, the auxiliary levers will in turn be raised through engagement of the heads 32 of the lifting screws with the underside 105 of the auxiliary levers at the bifurcations.

Springs 57 engaging the spring screws 58, urge the copper contacts 59, 60 and 61, 62, respectively of the auxiliary levers 49 and 50 into engagement. These contacts are 110 respectively screwed into the auxiliary levers and into the bases 16 and 17 as shown in Figures 3, 6 and 8.

The operation is doubtless obvious enough to the reader. Upon release of the operating button 20, the main spring 37 will press upwardly on the main key lever 19, rocking the latter on its fulcrum 41, consequently separating the tips 10 and 23 of the main contact A. The rocking movement of the main key lever, under this circumstance, is limited by the thumb screw 45 and strike pad 46.

The auxiliary contacts *a* and *b* will not 125 separate immediately upon release of the main contact lever 19, but the tips 59, 60 and 61, 62 will remain in engagement until the heads 32 of the lifting screws 28 and 29 engage the bifurcations of the auxiliary levers. The order of opening and closing of the 130

various contacts is easily regulated by the adjusting means shown in connection with the individual contact, so that such contacts may all open together or in sequence, as 5 may be desired. The key is normally adjusted for the following sequence.

Order of closing a—b—A
Order of opening A—b—a

- 10 The manual key performs the dual function of transferring the circuits from sending to receiving, without the medium of the usual send-receive switch. It permits the reception of a highly amplified signal with-
15 out interference from the local transmitter, and it tends to speed up traffic by making the telephones instantly responsive whenever the key lever 19 is released. The main and auxiliary contact levers may be made
20 of metal of low specific gravity, as, for example, aluminum and its compositions, in order to reduce the mechanical inertia in the operation thereof.

Attention is directed to Figure 11. In-
25 stead of mounting the main key lever 19 on a shaft 41 as in Figure 4, it may be mounted on cone-pointed screws 74, which are capable of adjustment and are fixed in such adjustment by means of jam nuts 75. The conical
30 points of the screws enter corresponding recesses in the sides of the key lever. It is readily seen with what ease the key can be disassembled, particularly when the arrangement 74 and 75 in Figure 11 is em-
35 ployed.

In conclusion, it may be stated that the manual break key described above, is related to our co-pending application for Letters Patent for wireless telegraph apparatus, 40 filed October 25, 1920, Serial No. 419,231, which describes a relay for receiving amplified signals from either a damped or undamped wave distant transmitter between the dots and dashes of the transmitter of
45 the local station. Both instruments, i. e., the relay of the co-pending application and the break key herein disclosed, are alike in this, that both receive the signals when the key lever is released, thereby speeding up
50 the handling of messages both outgoing and incoming.

There is another distinction between the two devices mentioned; the quick-acting break key of the co-pending application op-
55 erates as a result of the manipulation of a hand key which is associated therewith, while in the present instance, those instru-
60 mentalities which produce the functioning of the invention, are embodied directly in the hand key, and it is for that reason that the present invention is entitled a manual break key.

It is regarded as important to here define the major defects of break keys in common
65 use, which have been observed to be as

follows: (a) sluggishness of operation, (b) noisy reception, (c) rugged contact detector required, (d) inaccessibility and unreliability of adjustment, (e) frailness of construction, (f) multiplicity of contacts. It will 70 become more evident to the reader from the description below, that these defects are entirely cured in the improved break key, and in order that the construction and operation may be understood, the description is di-
75 rectly entered.

While the construction and arrangement of the improved wireless telegraph apparatus as herein described and claimed, is that of a generally preferred form, obviously 80 modifications and changes may be made without departing from the spirit of the invention or the scope of the claims.

We claim:—

1. A break key, comprising a main contact lever, with means normally opening it; auxiliary contact levers with means normally closing them, and means for forcibly opening the auxiliary levers against the influence of their closing means after a predetermined 90 opening movement of the main lever under the influence of its opening means.

2. A break key, comprising a main contact lever, with means normally opening it; auxiliary contact levers with means nor-
95 mally closing them, means for forcibly opening the auxiliary levers against the influence of their closing means after a predetermined opening movement of the main lever under the influence of its opening means, and 100 means embodied in said auxiliary lever-
opening means for regulating the order of opening movement of said levers.

3. A break key, comprising a main lever with contacts, and resilient means normally 105 forcing a separation; a plurality of auxiliary levers with contacts, and resilient means normally forcing engagement; means carried by the main lever for forcibly separating the auxiliary lever contacts against 110 the influence of their resilient engaging means when said main lever contacts are separated by the influence of its resilient means; and means embodied in said sep-
115 arating means for adjusting them in respect to the main lever to variously regulate the order of said forcible separation.

4. A break key, comprising an insulating base, a metallic trunnion with standards piv-
120 otally supporting a main contact lever, a main contact on the lever cooperating with a similar contact on the base, adjustable resilient means normally separating the contacts, auxiliary metallic trunnions mounted on the base, pivotally carrying auxiliary contact levers, auxiliary contacts carried by the levers cooperating with like contacts on aux-
125 illiary contact bases, mounted on the insulating base, adjustable resilient means, nor-
mally pressing the auxiliary contacts into 130

engagement, and independent adjustable means carried by the main lever, operatively associated with the auxiliary levers for forcibly separating the auxiliary contacts against their resilient means upon the separation of the main lever contact under the influence of its resilient means.

5. In a break key, an insulating base, with a metallic stud having a bored end; 10 a metallic contact base fixed on the stud flush with the end, a metallic contact fitted into the bore to surmount the base, and a movable key lever with a corresponding contact.

6. In a break key, a main key lever with

a bored enlargement, an insulating plug 15 fitted into the bore, a metallic plug carried by the insulating plug, a lifting screw adjustable in the metallic plug, and means for fixing the adjustment of said screw.

7. In a break key, a main key lever with 20 an insulatively mounted lifting screw including a reduced shank and a head, and an auxiliary lever having a bifurcated end occupied by the shank, lifted after a predetermined movement of the main key lever when 25 said head engages the auxiliary lever.
